GARMENT FOLDING EQUIPMENT

James W. Steele, North Kansas City, Mo.

Application December 21, 1950, Serial No. 201,946

8 Claims. (Cl. 223—37)

1

The present invention relates to garment folding apparatus, with particular reference to the type of equipment provided with folding devices designed for laundry finishing operations in which a shirt or other finished garment is required to be neatly folded into compact finished form as a necessary step in connection with packaging operations or the like.

A special object of the invention is to devise improved folding equipment in a single and unique form of apparatus adapted for convertible or alternative types of folding operation, whereby provision is made for carrying out not only the necessary folding operation or movements as required for the so-called long and narrow type of fold as in the conventional type of men's shirts, but which is also adapted by certain improved features of construction to carry out readily and efficiently the process of folding movements as required for producing the relatively shorter and wider folds in men's garments, such as sport shirts, pajamas etc., for which purpose the folding elements of the improved apparatus are arranged to be readily adjusted for the carrying out of either form of folding operation as desired, or according to requirements.

In its present improved and preferred form, the invention comprises a construction providing a table or supporting surface especially adapted for the carrying out of either of the types of folding operation referred to, including provision for accommodating either the conventional form of men's dress shirt in folding position, or the sport or pajamas type of garment requiring the shorter and wider folding operation. Accordingly said improved construction is characterized by an arrangement of folding or guide arms adapted to assume various operative positions relative to the top or working face of the table, as controlled by the operator, and including one set of such arms which are confined to use only in connection with the folding of sport shirts and the like, and another set of arms adapted not only for carrying out the folding operation or process required for dress shirts but is also adjustable into position for cooperating with said first set of arms in carrying out the folding procedure as required for said sport types of men's garments.

Incidentally, the invention is also directed to a type of garment folding equipment in which the construction is adapted for a folding procedure in which provision is made for the usual steps involving the insertion of suitable cardboard or stiffening elements, as well as the application of

2

wrapping bands, as may be desired in connection with the conventional wrapping or packaging procedure.

With the foregoing general objects in view, the invention will now be described in detail by reference to the accompanying drawings illustrating one of the preferred forms of construction which I have found to be both practical and efficient for the accomplishment of the desired purposes of the invention as above indicated, after which the various improved features and combinations thereof deemed to be novel and patentable will be particularly set forth and claimed.

In the drawings—

15 Figure 1 is a perspective view illustrating a shirt or garment folding apparatus constructed in accordance with my present invention;

Figure 2 is a perspective view (on a somewhat larger scale) showing only the upper portion of 20 said apparatus and representing certain of the folding or guide arms adjusted outwardly to different operative positions;

Figures 3 and 4 are similar perspective views 25 illustrating still other operative positions or relations of said folding or guide arms, as hereinafter explained;

Figure 5 is a perspective view illustrating all 30 of the folding or guide arms raised and thrown back into inoperative position, to disclose the table top structure underlying the folding or hinge leaf member which carries the two sets of folding or guide arms;

Figure 6 is a detail view of said folding or hinge leaf member, illustrating the connections 35 therewith, of said folding or guide arms;

Figure 7 is a detail sectional view (on a larger scale), representing a section taken on the line 7—7 of Figure 6; and

Figure 8 is a detail sectional view representing 40 a section taken on the line 8—8 of Figure 7.

The present improved apparatus, as illustrated in the aforesaid drawings, embodies certain improved features in the type of garment folding apparatus shown in my copending patent application Serial No. 178,041, filed August 7, 1950.

Referring now to the accompanying drawings in detail, and more particularly to Figure 1 thereof, this view represents a complete machine or apparatus embodying the present improved construction, comprising an upright body or framework 12 formed with a top or table portion 14 which provides the working or supporting surface for the garment folding operation, while the interior of the body or frame portion 12 serves 55 as a storage compartment 16 provided with a

shelf member 17 for suitable supplies of material as required for use in connection with the folding operations.

The top surface or working face of the table 14 is specially constructed for the laying of a shirt or other garment thereon in fully-spread relation and with the front of the garment facing downward; and for accommodating the conventional form of dress shirt, the rear portion of the table top is provided with a collar form or recess 18 for receiving the collar portion of the shirt when the same is placed in position for folding; whereas, for accommodating the sport type of shirt an alternative form of shallow type of collar well or depression 22 is located between the collar recess 18 and the front of the table for receiving the collar portion of the sport type of garment when the latter is positioned on the front portion of the table for the folding operation, all as shown in Figure 5 of the drawings.

From this latter collar recess or depression 22 a dado type of groove 24 extends to the front edge of the table for the purpose of accommodating the button and buttonhole pleats of the garment when thus spread in folding position, thus facilitating the work of definitely alining the garment in true and accurate position on the working face of the table, in preparation for the successive steps of the folding operation.

There is also provided a set of friction strips or pads 26 of soft gripping material (such as rubber or felt) suitably located adjacent to the outer sides of the table, for preventing any casual sliding or slipping of the garment during the folding process; and extending from the front to the rear of the table, between said friction pads 26 and the collar recesses 18 and 22, are located a pair of grooves or channels 28 forming receptacles in proper position for the storage of shirt wrapping bands 30 at a level below the top surface of the table, thereby facilitating the lifting of said bands into position for applying the same at both ends of a folded sports type of garment. A similar groove or channel 28' is also arranged crosswise of the table for holding a supply of the said bands 30 in readiness for applying the same to the folded dress type of shirt in the regular manner.

The top or working face of the table is still further provided at opposite front corners with a pair of guide strips 34, in parallel relation, the distance between said strips corresponding to the width to which the sports type of garment is to be folded. The front margin of the table is also preferably provided with ledge-like projections 36, adapted to define the first transverse fold-line of such garments, as well as to properly confine the garment in its initial folding position.

As in my aforesaid co-pending application, the present construction also employs a hinged leaf or panel member 40, carrying an assembly of folding or guide arms which are adapted to be properly positioned for the carrying out of the desired garment folding operations.

In the present improved construction this hinged leaf and folding arm assembly comprises a leaf or panel member 40 which is hingedly mounted by means of a transversely extending hinge structure 42 at the rear of the table top 14, the width of said member 40 corresponding to the space between the channels or receptacles 28 for the bands 30, and the length of said leaf member 40 being such as to extend (when lowered into working position) to the forward ends of the friction strips or pads 26, these dimensions

representing approximately the width and length to which a dress type of shirt is to be folded.

Mounted for sliding movement upon the upper face of the leaf or panel member 40 is a transverse plate 44 provided with a guide-block structure 46 which is mounted slidingly in a slot 48 extending from the hinge structure 42 and along the middle line of the leaf member 40 for approximately half its length. This transverse plate member 44 thus serves as an adjustable support for the folding and guide arms, all of which are of substantially the same length and are shown as comprising two pairs of arms, viz., an adjustable pair of arms 50 for use in both dress shirt folding and in sport shirt folding operations, and also an auxiliary pair of arms 52 designed as a reserve feature for cooperating with the arms 50 in one of the operative positions of said arms 50, i. e., when the latter have been adjusted into position for sport-shirt folding. The inner hinge ends of this reserve pair of auxiliary arms 52 are mounted in hinge-bearing elements 53, which are located at the outer rear corners of the said transverse or sliding plate 44.

The construction which is provided for adapting the folding arms 50 to be moved or shifted and set in their two different or alternative operative positions, is illustrated more particularly in Figures 6, 7 and 8 of the drawings. This construction comprises a pair of hinge blocks 54 mounted for sliding adjustment along a pair of alined slots 56 formed in the transverse plate 44, each of said blocks 54 being provided with a pair of bearing portions 58 for pivotally supporting the inner hinge end of one of the fold arms 50; also between each pair of bearings 58 is located a coil spring 60 carried by the corresponding hinge end and so engaged with the outwardly projecting portion of the arm as to actuate the same normally outward toward the side of the table.

Thus the arrangement and construction of the two hinge mountings is such that the spring elements thereof tend to throw the two arms 50 normally outward, into their outwardly-spread relation, as illustrated in Figures 1, 2 and 6.

For enabling the operator to position the fold arms 50 in either of their two operative positions, i. e., either in their widest spread relation as represented in Figure 2 for ordinary dress shirt folding, or in their retracted position as represented in Figures 1, 3 and 4 for sport-shirt folding, each of the hinge blocks is provided with a manually-operative device comprising a thumb or finger engaging knob 62 having a stem portion 63 carrying a disk element 64 engaging underneath the corresponding slot 56 and maintained in yielding engagement with the under side of the plate 44 by means of a coil spring 66 mounted on the stem portion 63. For securely latching the blocks 54 at the outer ends of the slots 56, each of said slots is formed with a slight depression 68 (see Figures 7 and 8) for seating and anchoring the disk element 64 to securely retain the block at said outer end of the corresponding slot, which conforms to the widest-spread relation of the fold arms 50 as represented in Figure 2.

It will therefore be apparent that the described construction is designed to secure proper placement of either dress shirts or sport garments for the folding operation and to retain the garment in a correctly alined state throughout the folding process as performed by use of either of the two different or alternative operative relationships of the fold arm assembly, according

to the particular adjustments, as made by the operator in charge of the apparatus.

Preparatory to the operation of folding conventional dress shirts, and starting with the equipment as arranged in the view shown in Figure 1, the operator pushes the hinge leaf or panel 40 (together with its fold arm assembly) to the rear of the table, and then adjusts the hinge blocks 54 carrying the pair of arms 50, by means of the knobs 62 for the purpose of sliding the blocks to the outer ends of the slots 56—as represented in Figure 2, in which position the said blocks are securely held by the engagement of the disks 64 with the depressions or sockets 68. The panel or leaf member 40 and its arm assembly are then raised and swung rearward against an upright backstop member 70 provided at the rear of the apparatus, and at each side of which are also arranged receptacles 72, as well as a rack member 73 at the rear of said backstop, for the holding of cardboard supplies 74 in convenient reach of the operator. The space between these receptacles or holders 72 at the base of the backstop member 70 is also utilized for locating a type of cuff-folding means 75 in conveniently accessible relation to the folding operation.

In folding the conventional dress type of shirt the same is spread face-downward upon the table, with its collar portion inserted within the rear collar recess 18; and after insertion of the usual shirt-stiffening board the panel or leaf member 40 is swung back down, on to the garment, in which operation the auxiliary fold arms 52 remain in inoperative position at the rear, as illustrated in Figure 2. The shirt is then folded in accordance with the usual method, by the operator's movements combined with the successive inward folding of the arms 50, for producing the long and narrow type of fold for such conventional or dress type of shirt. In this connection, suitable stops or buffers 76 are arranged at the sides of the table for engagement by the arms 50 when the latter are swung outward into their outermost positions—as shown in Figure 2.

In changing from the operation of folding regular dress shirts to the operation of folding sport shirts or the like, the operator simply depresses the knobs 62 and then pushes the hinge blocks 54 inwardly or toward each other, as represented by the intermediate position indicated in Figures 6 and 7 and also the final adjusted position of said blocks and the corresponding or new position of the fold arms 50 (in approximate alinement with the guide strips 34), as shown in Figure 3. The operator then pushes the crossplate 44, carrying the fold arm assembly, forward to the position illustrated in Figure 4, which thus provides a folding equipment that is adapted for the carrying out in all respects the same method of folding operation for the sports type of garments as outlined and set forth in my aforesaid co-pending application Serial No. 178,041, filed August 7, 1950.

It will thus be apparent that I have devised a practical and most efficient form of apparatus for attaining all the aforesaid objects of my invention, as regards a unitary equipment having the necessary "convertible" features for embracing all the operative means required for the folding of both dress and sport types of garments, all within the same unitary apparatus; and in this connection it is further important to note that an outstanding advantage characterizes said improved construction by virtue of the fact that substantially the same size of reinforcing or stiffen-

ing cardboards may be utilized for both folding procedures, thereby resulting in a major factor of economy or savings in connection with the cost-outlay involved in this particular industry to which the present invention and improvements are related.

From the foregoing it will therefore be apparent that I have devised a practical and comparatively very simple construction for the carrying out of the several purposes of the invention as herein stated; and while I have shown and described what I now regard as one of the preferred forms of construction for embodying my novel and improved features, I nevertheless desire to be understood as expressly reserving the right to make whatever changes or modifications may fairly be deemed to fall within the spirit and scope of my invention as defined by the appended claims.

What I claim is:

1. Garment folding apparatus comprising, in combination, a table member, a movable leaf member hingedly mounted on said table member for swinging movement into and out of operative relation to the upper working face of the table, and a set of garment folding and guide arms pivotally mounted on said leaf member and also slidably adjustable thereon into different operative positions both longitudinally and transversely with reference to said leaf member.

2. Folding apparatus for shirts and like garments comprising, in combination with a table member, a leaf member hingedly mounted on said table member for swinging movement into and out of garment folding relation to the upper face of said table, a pair of garment folding arms carried by said leaf member and slidably adjustable thereon into different spread relations for varying types of the garment folding operation, and supplemental folding arms also hingedly supported by said leaf member for independent movement into co-operative relation to said first folding arms for producing one of said types of folding operation.

3. Garment folding apparatus comprising, in combination, a table member, a movable leaf member adapted to be swung into and out of operative relation to the upper working face of the table, a set of garment folding and guide arms pivotally mounted on said leaf member and also slidably adjustable thereon into different operative positions transversely of said leaf member, and a second set of folding and guide arms movable into position relatively to said working face of the table for cooperating with said first set of arms in one of the adjusted positions of the latter in the garment folding operation.

4. Garment folding apparatus comprising, in combination, a table member, a movable leaf member adapted to be swung into and out of operative relation to the working face of the table, a pair of garment folding and guide arms pivotally mounted on said leaf member and also slidably adjustable thereon into different operative positions transversely of said leaf member, and a second set of folding and guide arms movable with said first set of arms into position for cooperating therewith in one of the adjusted operative positions of said first set of folding arms.

5. Garment folding apparatus comprising, in combination, a table member, a movable leaf member adapted to be swung into and out of operative garment folding relation to the upper working face of the table, two independently mounted sets of folding and guide arms carried

by said leaf member and slidably adjustable thereon into different longitudinal positions with reference to said leaf member and one of said sets of arms being also adjustable transversely of said leaf member for garment folding operation either independently of or in cooperation with said first set of arms for different types of garment folding processes.

6. Garment folding apparatus comprising, in combination, a table member, a movable leaf member adapted to be swung into and out of operative garment folding relation to the upper working face of the table, a transverse plate carried by said leaf member and mounted thereon for sliding movement longitudinally of said leaf member, two sets of folding and guide arms pivotally mounted on said plate for independent movement into and out of operative garment folding position with relation to said working face of the table and one of said sets of arms being slidably adjustable upon said transverse plate for positioning said arms in different operative positions relative to said working face of the table for garment-folding operation either independently of or in cooperation with the other set of said folding and guide arms.

7. Garment folding apparatus comprising, in combination, a table member, a movable leaf member adapted to be moved into and out of operative relation to the working face of said table, a transversely extending plate carried by said leaf member for sliding adjustable movement longitudinally of the leaf member, a pair of garment folding and guide arms pivotally

5 10 15 20 25

mounted on said transverse plate and adjustable therewith into different operative garment-folding positions relative to the leaf member, and a second pair of garment folding and guide arms mounted on said transverse plate independently of said first arms and adapted to be swung into cooperative garment-folding relation therewith in one of the operative positions of said first arms.

8. Garment folding apparatus comprising, in combination, a table member, a movable leaf member adapted to be moved into and out of operative garment-folding relation to the upper working face of the table, a set of garment folding and guide arms pivotally mounted on said leaf member and also slidably thereon into different operative positions transversely of said leaf member, a second set of folding and guide arms independently movable into position relative to said working face of the table for cooperating with said first set of arms in one of the adjusted working positions of the latter in the garment folding operation, and means for latching and securing said first set of arms in one of the adjusted operative positions of said arms.
